STEREO TAPE RECORDER

Eugene J. Freeman, 11458 Laurel Crest Road,
Studio City, Calif.

Filed Apr. 29, 1964, Ser. No. 79,731

Term of patent 14 years

(Cl. D26—14)

FIG. 1 is a front, top and right side perspective view of a stereo tape recorder, showing my new design;

FIG. 2 is a left side elevational view thereof; and

FIG. 3 is a rear elevational view thereof.

The grille coverings are conventional and continuous over the side and rear areas shown. Portions of FIG. 1 are lined diagonally to indicate transparency.

I claim:

The ornamental design for a stereo tape recorder, as shown and described.
